(57) **CLAIM**

The ornamental design for a card holder for jewelry, as shown and described.

DESCRIPTION

FIG. 1 is a top plan view of a card holder for jewelry showing my new design;

FIG. 2 is a front elevational view thereof, with the opposite side being a mirror image;

FIG. 3 is a side elevational view thereof, with the opposite side being a mirror image; and,

FIG. 4 is a bottom plan view thereof.

The broken lines shown are for illustrative purposes and form no part of the claimed design.
